UNITED STATES PATENT OFFICE.

GEORGE D. JORDAN, OF CLEVELAND, AND CLYDE A. BRADEN, OF LAKEWOOD, OHIO.

AUTOMATIC CONTROL DEVICE FOR IRONS.

Application filed June 25, 1923. Serial No. 647,442.

This invention relates to electric heating devices and more particularly to electric irons.

It is one of the objects of the invention to provide means for automatically shutting off the current to prevent overheating of the iron.

It is a further object of the invention to provide means for automatically turning on the current after the iron has cooled down sufficiently, after the automatic cut-off has operated.

A further object of the invention is to provide a comparatively simple and inexpensive device, for the purposes specified, that will be adapted to be applied to existing irons and will not interfere in any way with the insertion or removal of the ordinary detachable plug for connecting the supply line to the iron.

Other objects of the invention and the features of novelty will be apparent from the following description taken in connection with the accompanying drawings, of which:

Figure 1 represents a side elevation of an iron having our invention applied thereto, certain parts being shown in section;

Fig. 2 is an end elevation thereof;

Fig. 3 is a section of a structure embodying our invention, detached from the iron, certain parts being shown in section;

Fig. 4 is a view similar to Fig. 1 but showing a modification of the invention;

Fig. 5 is a view similar to Fig. 4 but showing still another modification; and

Fig. 6 is a transverse section of a modification of one of the details of the invention.

Referring to the drawings and particularly to Figs. 1 to 3, 10 indicates an ordinary heating iron having the usual brackets and grip constituting a handle 11. At the rear of the iron are the usual contacts 12 with which a removable attachment plug 13 operates for the purpose of supplying the heating current to the iron. The plug 13 is of the type embodying a so-called "push" switch actuated by the usual push buttons 14 and 15. The details of this switch are not shown on the drawings because it is a well-known type of switch and the construction and operation are well understood. We attach to the rear bracket of the handle 11 a bracket 16 that is secured to the handle in the manner shown in Fig. 1 and extends downwardly and is attached to the rear of

the iron by means of the lugs 17 and the screws 18 which are best shown in Fig. 2. The bracket 16 may be formed of sheet metal or may be a casting and, when formed of sheet metal, may be stamped from a sheet of flat stock folded up into the form shown, the edges meeting at the back, as indicated at the point 20. Adjacent to the lugs 17, the bracket 16 is provided with a boss 21 into which a plug 22 is threaded (see Fig. 3). The plug 22 has secured thereon a small disc-like container 23 having a flexible diaphragm 24 closing its outer end. This container 23 is partially filled with a volatile liquid such as alcohol and sealed up tight.

The bracket 16 has two rearwardly projecting lugs 25 on which the lever 26 is pivoted, as indicated at 27. The lower end of the lever 27 carries an adjustable screw 28 which cooperates with the diaphragm 24, as best shown in Fig. 1.

The bracket 16 is formed with a collar or other means to surround and support the plug 13 and the upper end of the lever 26 is so arranged as to engage the button 14 of the switch for the purpose of actuating the latter.

A spring 29 is secured on the bracket 16 by rivets 30 or in any other suitable manner, and when the plug 13 is inserted the buttons 14 and 15 enter between the upper end of the lever 26 and the spring 29, preferably putting the latter under tension.

In the operation of the device just described the parts will be arranged, substantially as shown in Fig. 1, when the iron is being heated. The heat absorbed by the lower end of the bracket 16 will be conducted through the plug 22 to the container 23 and cause the alcohol in the container to be evaporated, thus generating pressure within the container which will force out the diaphragm 24 and this, in turn, will move the lever 26 and push in the button 14 and thus cut off the current in case the heat in the iron becomes too high. When the button 14 is pushed in, the button 15 will be pushed out against the tension of the spring 29 and when the iron cools sufficiently the vapor in the container will condense and thus reduce the pressure sufficiently to permit the spring 29 to push in the button 15 and thereby turn on the current.

Instead of using a container having a flexible end wall we may use a container of the type illustrated in Fig. 6, which con-

sists of the corrugated side walls 31, formed of relatively thin metal and the end plates 32 and 33, the plate 32 bearing the plug 22. With a container of this type the pressure 5 on the interior would tend to separate the end walls and thus produce the same effect as the outward bulging of the diaphragm 24. It will, therefore, be understood that where, in the claims, we mention the container, either of the forms illustrated in 10 Figs. 1 and 6 may be employed.

In the form of the invention illustrated in Figs. 1 to 3 the container 23 is positioned vertically, or substantially so, and for some 15 reasons this arrangement is preferable because it permits the container to be brought fairly close to the iron. In the form illustrated in Fig. 4 the container 34 is arranged horizontally, with the plug 22 in a vertical 20 position. The lever 35 is in the form of a bell crank pivoted at the point 27, as in the other form. In this construction one arm of the lever 35 is much shorter than the other and the short arm carries an adjusting screw 36 for cooperation with the diaphragm 37. The long arm of the lever 35 cooperates with the button 14 of the switch and the arrangement provides for a multiplication of the movement of the short arm 25 so that relatively small movements of the diaphragm 37 will actuate the switch button 14. In this form of the invention, we have omitted the spring 29 but it will be understood that the use of this spring is optional in either form.

In the form of the invention illustrated in Fig. 5 we provide, on the rear of the iron, a container 38 having a hollow extension 39 to the upper end of which the expandable 40 member 40 is attached. We have shown this expandable member as being provided with flexible diaphragms at its ends but it will be understood that the form used in Fig. 6 may be employed. In this case, the 45 button 14 of the switch may contact with the outer diaphragm 41.

In the operation of this form of the invention, the volatile liquid in the container 38 is vaporized by the heat from the iron, 50 which results in an accumulation of pressure in the container and this pressure, being transmitted through the passage 39' of the extension 39, and the passage 22' in the plug to the interior of the member 40, forces 55 out the diaphragm 41 which causes the button 14 to be actuated to shut off the current.

The form illustrated in Fig. 5 has advantages in that it is very simple to construct and is so closely arranged with reference to 60 the rear of the iron and the attachment plug 13 that it is not liable to injury through striking objects when the iron is moved backward. This form of the invention is also simpler than the other forms in that 65 the levers 26 and 35 are eliminated. The

spring 29 for turning on the current may be used with this form of the invention as well as with the other forms, as will be perfectly obvious from Fig. 1. The bracket 16' which supports the attachment plug 13 may 70 be of the form ordinarily employed on commercial types of irons.

While we have intended our invention to be applicable primarily to electric irons yet it will be understood by those skilled in the 75 art that it is also applicable to other forms of electric heating devices and it is the intention to have the claims cover such other uses as the invention is adapted for. It will also be understood that the expandable 80 member shown in Fig. 6 may be readily substituted for the one shown in the other figures and we, therefore, desire to have the claims construed as including the expandable member shown in Fig. 6.

Having thus described our invention, what we claim is:

1. The combination of an electrically heated device, thermostatic means attached to said device and adapted to be heated thereby, switch actuating means associated with said thermostatic means and actuated thereby, a readily removable and replaceable attachment plug for connecting a source of electric current to said device, and a switch 90 in said plug, for controlling the current, arranged in position to be actuated by said actuating means when said plug is in its attached position on said device.

2. The combination of an electrically heated device, thermostatic means attached to said device and having associated therewith means actuated by the thermal element thereof, a lever mounted on said device and having one end in cooperation with the last-mentioned means so as to be actuated thereby, a readily removable and replaceable attachment plug, for connecting a source of electric current to said device, having a switch mounted thereon, and actuating means for said switch arranged to cooperate with said lever and be actuated thereby when said plug is in position on said device.

3. The combination of an electrically heated device, thermostatic means attached to said device and having associated therewith means actuated by the thermal element thereof, a lever mounted on said device and having one end in cooperation with the last-mentioned means so as to be actuated thereby, a readily removable and replaceable attachment plug, for connecting a source of electric current to said device, having a switch mounted thereon, actuating means for said switch arranged to cooperate with said lever and be actuated thereby, to shut off the current, when said plug is in position on said device, and means for automatically actuating said switch to turn on the current.

4. The combination with an electric iron,

of a handle thereon, a bracket attached to said handle and to said iron, an expansible container mounted on said bracket, a lever pivotally mounted on said bracket and having one end operatively connected with said container, said bracket having means to receive and support an attachment plug, and an attachment plug, for connecting a source of electric current to said iron, having a switch thereon adapted to be actuated by said lever when said plug is positioned in said means.

5. As an article of manufacture for the purpose described, a device for attachment 15 to an electrically heated device to automatically control the supply of current thereto and comprising means for receiving and holding an attachment plug that is provided with a switch, a container for a volatile liquid having associated therewith means actuated by the pressure in the container, and a lever actuated by the last-mentioned means and arranged to actuate said switch when said plug is in position in said receiving and holding means.

20 6. As an article of manufacture for the purpose described, a device for attachment to an electrically heated device to automatically

control the supply of current thereto and comprising, in combination, means for receiving and holding an attachment plug that is provided with a switch, a container for a volatile liquid having a flexible diaphragm at one end adapted to be expanded by the pressure in the container, and a pivoted lever having one end operatively connected with said diaphragm and arranged to actuate said switch when said plug is in position in said receiving and holding means.

7. The combination with an electric iron 40 of a bracket secured to the rear thereof and having an opening to receive an attachment plug, thermostatic means secured to said bracket, a vertically extending lever having one arm arranged to be actuated by said thermostatic means, and another arm arranged to actuate a switch in the attachment plug when the latter is positioned in said opening, the parts being constructed and arranged to, at all times, freely permit the attachment plug to be inserted into and removed from said opening.

In testimony whereof we affix our signatures.

GEORGE D. JORDAN.
CLYDE A. BRADEN.
